UNITED STATES PATENT OFFICE.

JOSEPH C. O'NEILL, OF NEW YORK, N. Y.

DRESS-SUIT CASE.

1,150,058.

Specification of Letters Patent.

Patented Aug. 17, 1915.

Application filed June 6, 1914. Serial No. 843,445.

To all whom it may concern:

Be it known that I, JOSEPH C. O'NEILL, a citizen of the United States, and a resident of New York, borough of Brooklyn, 5 county of Kings, and State of New York, have invented certain new and useful Improvements in Dress-Suit Cases, of which the following is a full, clear, and exact description.

10 This invention relates more particularly to an extended or foldable dress suit case or similar device in which articles of apparel can be placed without creasing or folding and which device is adapted to hold 15 various kinds of articles.

One of the principal objects of the invention is to provide a simple and efficient dress suit case having a plurality of members which are hinged together so as to 20 adapt the members to be moved to an unfolded position and in such position adapted to have large articles of apparel, such as suits of clothes, dresses, etc., supported and hung therein in a manner similar to placing 25 such articles in a wardrobe or similar place, and which members, while the articles are thus held, may be moved to a folded position and locked without any folding or creasing whatever of the large articles 30 placed within the device.

Other objects of the invention are to provide simple and efficient means whereby the large articles of apparel may be held in such a way that pressure will not be made against 35 such articles by other articles placed within the suit case; to provide means whereby various toilet and other articles may be properly held within the device; to provide means for separating the large articles from 40 the smaller ones and to cause a tension to be exerted against a certain part of the articles to force the same with a gentle bend within one member of the suit case; to provide simple and efficient partitions and 45 means for supporting the same within the casing; and to provide means whereby collars and like articles may be held.

Another object of the invention is to provide an extensible or foldable suit case 50 which may have the general form and appearance of a suit case as ordinarily used and which may be made of leather, wicker-work, or of any other suitable material.

A further object of the invention is to 55 provide a suit case in which one member

forms a receiver for a part of the larger articles placed within the device and which member is of such a form as will prevent ready access of water in case the suit case is placed on the ground in wet weather. 60

A still further object of the invention is to provide a suit case which is simple in construction and which may be readily made and assembled.

A still further object of the invention is to provide means whereby the members may be suitably held with relation to each other and one member positively locked to another member when in a folded or closed position. 65

With these and other objects in view, the invention will be hereinafter more particularly described with reference to the accompanying drawings, which form a part of this specification, and will then be pointed 70 out in the claims at the end of the description. 75

In the drawings, Figure 1 is a perspective view of one form of device embodying my invention, showing the said device in an extended or unfolded position. Fig. 2 is a section, taken on the line II—II of Fig. 3, with the parts of the device in an open or extended position. Fig. 3 is a plan view of the device with the parts in an open position as shown in Figs. 1 and 2. Fig. 4 is a cross section of the device in a closed or folded position. Fig. 5 is a fragmentary view, partly in section, showing how one of the partitions may be supported within the 80 device. Fig. 6 shows a somewhat different form of partition; and Fig. 7 is a section taken on the line VII—VII of Fig. 6. 85

The body of the device comprises essentially a bottom member 10, a back or rear member 11, and a front or top member 12. The member 10 is box-like in form having end walls 13 and front and rear walls 14. The members 11 and 12 are hinged, at 15, by leather strips or otherwise, to the upper 95 edge of the front and rear walls of the member 10 so that in an open position they may be moved outward to form an extended device as shown in Figs. 1 to 3, or the said members 11 and 12 may be moved on 100 their hinges toward each other to a folded or closed position as shown in Fig. 4. The member 11 has a wall 16 which when in a folded position forms substantially a continuation of the rear wall 14 of the member 110

10, and a top wall 17 and end walls 18, which latter are adapted to form a continuation of the end walls 13 of the member 10 when the member 11 is in a folded or closed 5 position. This member 11 for a part of its depth and along the top wall 17 and part of the end walls 18 has a flexible member 19 of any suitable fabric and which may be secured at its inner edge to the member 11, 10 and at its upper edge shirred, at 20, and provided with an elastic in order to provide a series of flexible pockets 21 around the member 11 for the purpose of holding toilet or other articles which one may desire 15 to carry within the device. At the corners of the member 11 are bands 22 which may be tied together at their free ends to hold collars, cuffs, or other articles so that they will not be displaced while the device is 20 being transported.

In order that large articles as suits of clothes, dresses, etc., may be supported properly within the device without being first folded and thereby avoid creasing said articles, I provide the device with means whereby such articles may be suspended by hanging or otherwise, such means being capable of various constructions. As shown, a rod 23 is held to brackets 24 on the top 30 wall 17 of the member 11 and about which rod may be arranged one or more hangers on which the coat, trousers, or other garment is adapted to be held when the members are in the position shown in Figs. 1 to 3. When 35 in this condition, the entire device may be hung or supported from a hook by means of a carrying handle or strap 25 which is held to the wall 17 of the member 11, or the device may be arranged upon the floor as preferred. The suit of clothes without any 40 folding whatever is placed within the device lengthwise thereof and in this case the suit will extend over the bottom member 10. Two partitions 26 and 27 are provided, 45 the former held to the member 11 and the latter to the member 12. The partition 26 when the clothes are placed in position, is, of course, removed, and to permit the said partition to be readily attached to or 50 detached from the member 11, a plurality of socket pieces 28 are formed on the ends of brackets 29. These socket pieces 28 may be of any desired form and may be slotted and are adapted to receive large slotted ends 55 of a fastening device or member 31. This member 31, Fig. 5, may be carried by an arm or bracket 32 which projects outward from the tray or partition 26. There may be any suitable number of these detachable 60 fastening devices for the partition 26 though the drawings show four, one at each side edge and two at the outer edge thereof.

So far as the socket pieces 28 and the fastening element 31 are concerned, the construction is substantially the same as that of

the ordinary glove fastener, except, possibly, as to the size and stiffness of the parts and the means whereby these parts are mounted, the construction being such that the fastening elements are readily separable from and attachable to each other in order that the tray or partition 26 may be held to or removed from the device. The tray or partition 26 may have its body 33 somewhat smaller than the interior of the tray 11 and 70 may be of solid veneer or other material with a suitable covering therefor or may be of a skeleton form covered or not as preferred. This partition is suspended within the member 11 so as to provide a space 34 under the same for the clothes when hung upon the bar or rod 23, and said partition extends beyond the inner edge of the member 11 and is provided with a rounded portion 35 along one edge which when the device is folded for transporting purposes, the said end 35 will extend into the member 10. The purpose of this is to provide a space 75 in order that the weight of other articles placed within the device will not be on the clothes within the space 34 and to cause the end 35 of the partition 26 to force the clothes or apparel into the bottom 10 with a gentle bend and without any sharp crease so that the garment when in position for 80 transporting purpose will be substantially 85 U-shaped in form and simply bent within the member 10 without any creasing whatever. The garment is passed under the end 36 of the partition or tray 27 which end 36 is rounded similar to the end 35 for the 90 reasons stated. If a suit of clothes is being carried, the tray 27 may rest directly upon that portion which extends into the top member 12 of the suit case, but if a woman's 95 dress is to be carried without creasing or folding, in that case the partition 27 is supported away from the front of the member 12 by a suitable space, as 37, and if of sufficient length may then be folded about the 100 partition 27 over the top portion thereof. The partition 27 is suspended somewhat 105 differently from the partition 26, said partition being held to said member 12 by flexible straps or members 38 located at the outer 110 edge of said partition.

The flexible connections 38 may be detachable by suitable fastening devices, as fastening devices similar to that of glove fasteners, or may be permanently attached thereto, and said flexible members 38 may be held to the member 12 by metal loops or brackets 39. A plurality of pivoted fingers or members 40 are held at the opposite edges of the partition 27 and said fingers are adapted to 115 be positioned in alignment with the edge of said partition or to be moved at an angle thereto so as to form feet to separate said partition from the front of the member 12 120 in order to provide a suitable space between 125 130

said member 12 and the partition as already described. The partition 27 is suspended as shown when the case is in a folded condition by the flexible members 38 and the weight of 5 said partition serves to hold the garment in its proper bent position within the suit case member 10. This partition 27 is held against outward movement beyond a certain extent by a strap 41 which has its ends secured to 10 the member 12 and its inner free ends adapted to be fastened together. There are also straps or fastening elements 42 on the outer face of the partition 27 to adapt articles such as shirts or the like to be secured to 15 said partition 27, like means being also provided on the partition 26 if desired, and said partition 26 is so located as to provide a space outside of the same for placing various articles of apparel thereon.

20 A stay and locking device 43 is provided on each side of the suit case for the purpose of holding the member 11 properly to the member 10 in both the open and the closed position. The device 43 is of a special construction and is not claimed specifically herein as it forms subject matter of a separate application Serial No. 843,446 filed of even date herewith. As shown, each device 25 43 comprises an extensible member 44, one 30 end of which is pivoted, at 45, to a bracket 46 secured to one of the end walls of the suit case member 10. The extensible member 45 is bar-like in form and has an elongated slot 47, one end of said slot being hook-shaped, 35 as at 48, and adapted when the suit case is in a folded or closed position to pass about a projection 49 in a casing 50. A slide having a finger portion 51 is movable in the casing 50 and this slide has a pin mounted thereon, 40 not shown, which is also adapted to enter the slot 47 and serves to limit the outward movement of the member 44. The member 44 is intended to be of such length and is constructed in such a way that the back 45 member 11 may move relatively to the member 10 to the position shown by dotted line 52 of Fig. 2, the member 12 of the suit case being adapted to move also on its hinges to the position shown in dotted line 53 of said 50 figure. The members 11 and 12 may thus move to a position to prevent canting of the member 10 in order that the same may lie flat and the said device, when in an extended position, is adapted to rest directly on the 55 floor or other support or to be suspended by means of the handle 25. When the member 11 is in the position shown in Figs. 1 to 3, the members 44 serve as stays and braces for the member 11, and when the member 11 is 60 moved to the folded position shown in Fig. 4, the hooked end 48 of the members 44 will engage the pins 49 and positively lock the members 10 and 11 in such folded position and substantially at right angles to each 65 other. By moving the slides through the

finger pieces 51, the members 44 may be released from the pins 49 to permit the member 11 to be moved to an unfolded or extended position.

The case or other device is intended to be 70 provided with locks and clasps of the usual or of any preferred form and said case may have straps 54 which are secured to the member 10 and which have one end thereof extending about the member 12 and the 75 other end provided with a buckle and extending about the member 11 so that when the members are brought to a folded or closed position, the straps as well as the clasps may serve to positively hold the members together ready for transportation or 80 for other purposes.

In Figs. 6 and 7, a somewhat different form of partition is provided. Here the body 55 is of a skeleton form and has a central part 56. This part 56 is cut away, as at 57, and guided in said cut-away portion is a stem 58 of a rod 59. The stem 58 is provided with pins 60 which are adapted to engage shoulders of the cut-away part 57 90 to limit its outward movement, and said support is normally forced outward by a spring 61, one end of which is held to the stem 58 and the other end to the part 56. The rod 59 corresponds to and is for the 95 same purpose as the ends 35 and 36 of the partitions 26 and 27 respectively, and instead of the ends being fixed, the rod 59 is yielding held to the body of the partition through the spring 61. It will be understood that the body of the partition shown in Fig. 6 may be covered or not as desired and that the construction therein shown may be substituted for either or both of the partitions 26 and 27. 100

105 From the foregoing, it will be evident that a simple and efficient dress suit case or similar device is provided whereby clothes such as suits or dresses may be supported or carried therein without folding or creasing 110 the same; that simple means is provided whereby various articles may be held within the device without exerting any pressure whatever on the clothes; that simple means is provided whereby two of the members 115 may be properly held with respect to each other in either of their folded or unfolded position; that simple means is provided whereby partitions may be arranged within the members of the suit case and so supported that their ends may be made to rest against the garment or garments carried in the device; that said suit case has its bottom member so arranged and attached to the other members that water cannot have ready 120 access to the interior of the casing; and that said device is simple in construction and may be made with very little additional cost and of substantially the same weight 125 as that of an ordinary suit case. 130

Having thus described my invention, I claim as new and desire to secure by Letters Patent:—

1. A device of the character described, comprising a box-like bottom member, a back member hinged thereto, a front member hinged to the bottom member, and independent devices for connecting the bottom member to the back member which serve both as stays and as locking means. 5
2. A device of the character described, having a bottom member, a plurality of members connected to the bottom member, and independent devices for connecting the bottom member to one of said members which serve both as stays and locking means. 15
3. A device of the character described, comprising a shallow substantially box-like bottom member, a back member hinged at one edge of the bottom member and comprising rear, side and top walls, a shallow front member hinged along one edge of the bottom member and having front, top and end walls, and means having an extension member connecting the back member and bottom member together and forming a stay when in an unfolded position and a lock when the back member and the bottom member are brought to a folded or closed position. 20
4. A device of the character described, comprising a shallow substantially box-like bottom member, a back member hinged at one edge of the bottom member, a shallow front member hinged along one edge of the bottom member, and means having an extension member connecting the back member and bottom member together and forming a stay when in an unfolded position and a lock when the back member and the bottom member are brought to a folded or closed position. 25
5. A device of the character described, comprising a substantially box-like bottom member, a member hinged at one edge of the bottom member, a second member hinged along another edge of the bottom member, and means connecting one of the members and the bottom member together and forming a stay when in an unfolded position and a lock when said latter member and the bottom member are brought to a folded or closed position. 30
6. A device of the character described, comprising a bottom member, a back member hinged at one edge of the bottom member and comprising rear, side and top walls, a shallow front member hinged along one edge of the bottom member and having front, top and end walls, and means connecting the back member and bottom member together and forming a stay when in an unfolded position and a lock when the back member and the bottom member are brought to a folded or closed position. 35
7. A device of the character described, comprising a substantially box-like bottom member, a back member hinged to the bottom member along one edge thereof, a front member hinged along the opposite edge of the bottom member, and partitions supported in the back and front members and having a part projecting beyond said members so as to extend partly into the bottom member when the device is in a closed position. 75
8. A device of the character described, comprising a bottom member, a back member hinged to the bottom member, a front member hinged to the bottom member, and partitions supported in the back and front members and having a part projecting beyond said members. 80
9. A device of the character described, comprising a substantially box-like bottom member, a back member hinged to the bottom member at one edge thereof, a front member hinged at the opposite edge of the bottom member, and a partition supported in the back member and having a part projecting beyond said member so as to extend partly into the bottom member when the device is in a closed position. 85
10. A device of the character described, comprising a bottom member, a front member and a back member hinged together and adapted to be extended to an open position in substantially the same plane, and a rod serving as a hanger and held in one of said members by which rod articles of apparel may be supported within the device. 90
11. A device of the character described, comprising a bottom member, a front member and a back member hinged together and adapted to be extended to an open position in substantially the same plane, and means held in one of said members by which articles of apparel may be supported within the device. 105
12. A device of the character described, having a bottom member, a front member and a back member hinged together and adapted to be extended to an open position, and a rod serving as a hanger and held in one of said members by which rod articles of apparel may be supported within the device. 110
13. A device of the character described, comprising a bottom member, a front member hinged to said bottom member, a back member hinged to the bottom member opposite the front member, a substantially rectangular partition arranged in the back member and having one end projecting beyond the same, and means whereby the partition may be detachably held to said back member. 115
14. A device of the character described, comprising a bottom member, a back member hinged to said bottom member, a front 120
15. A device of the character described, comprising a bottom member, a back member hinged to said bottom member, a front 125
16. A device of the character described, comprising a bottom member, a back member hinged to said bottom member, a front 130

member hinged to the bottom member, a partition arranged within the front member and flexibly connected thereto and having one end projecting beyond said member, 5 fingers pivotally held at the edges of said partition, and means held to the partition whereby articles may be fastened and held thereto.

15. A device of the character described, 10 comprising a bottom member, a back member hinged to said bottom member, a front member hinged to the bottom member, and a partition arranged within the front member and flexibly connected thereto and having one end projecting beyond said member.

16. A device of the character described, comprising a bottom member, a back member hinged to said bottom member, a front member hinged to the bottom member, a

partition arranged within the front member, and fingers pivotally held at the edges of said partition.

17. A device of the character described, comprising a bottom member, a back member hinged to said bottom member, a front 25 member hinged to the bottom member, a partition arranged within the front member and flexibly connected thereto and having one end projecting beyond said members, and fingers pivotally held at the edges 30 of said partition.

This specification signed and witnessed this 4th day of June, A. D. 1914.
